FIG. 3

FIG. 4. 43

Inventor

Richard J. Wynkoop

Shambalar & Newman Attorney

UNITED STATES PATENT OFFICE.

RICHARD J. WYNKOOP, OF BRIDGEPORT, CONNECTICUT.

PHOTOGRAPHIC-PRINTING MACHINE.

1,403,884.

Specification of Letters Patent. Patented Jan. 17, 1922.

Application filed May 21, 1920. Serial No. 383,113.

To all whom it may concern:

Be it known that RICHARD J. WYNKOOP, a citizen of the United States, and resident of Bridgeport, in the county of Fairfield and State of Connecticut, has invented certain new and useful Improvements in Photographic-Printing Machines, of which the following is a specification.

The object of this invention is to provide 10 a photographic printing machine with an automatic paper feeding mechanism of such construction that by a single operation the proper amount of paper can be brought into position over the negative and the same 15 clamped properly in place.

Other objects consist in the provision of means for recording the printing operation and setting the recording device so that an 20 alarm is sounded for signaling the operator when the desired number of prints have been made. Still another object is to provide an arrangement whereby the lamps will be illuminated at the proper time by the 25 movement of the automatic paper feeding mechanism.

More specifically this invention consists in providing a light box construction for the reception of a negative and a negative retaining mechanism, and means for feeding 30 the print paper into position on the negative, the paper feeding mechanism being adapted to operate the illuminating means and when in normal position to engage and lock the pad over the print paper 35 and negative. Means are also provided for regulating the movement of the paper feeding mechanism to cause the proper amount of paper to be drawn forward and arranged over the negative, which latter may be of 40 different sizes to better accommodate pictures of different sizes.

For the specific construction and operation reference will be had to the accompanying drawings forming a part of this 45 specification and wherein, like numerals of reference designate corresponding parts throughout the several views, in which:—

Fig. 1 is a side elevation of my complete 50 printing box.

Fig. 2 is a top plan view.

Fig. 3 is a side elevation with the operating member raised and showing the feeding mechanism in extended position, and

Fig. 4 is a vertical section.

The invention comprises the table formed 55 of the top 1 and legs 2 and 3, which latter

are braced by the baseboard 4. Arranged adjacent the table top 1 and between the legs 2 and 3 is the light box 5 in which may be located any suitable number of incandescent lamps 6. The top of this box is formed by the table top 1 and a portion of the top forming the top of the box is cut away as at 7 and is grooved for the reception of a transparent plate 8. This plate 8 forms 60 the light transmitting opening through which the light penetrates for contact with the negative as will more clearly herein-after appear. The wall of the light opening 7 is cut away as clearly shown in Fig. 70 4 to form the shoulder 9 for supporting the negative indicated by reference character 10. A removable plate 11 having an opening therein is placed over the negative 10 to determine the size of the prints and may 75 be substituted from time to time by other plates having larger or smaller openings for different size pictures. A clamping frame 12 formed of thin sheet metal is hinged to swing on the pintle 13 which latter 80 is supported by the members 14—14' secured to the side of the table top. The free end of this frame 12 is provided with hooks 15—15' formed integral thereto and projecting downwardly and inwardly for engagement with the rod 16 which is mounted similarly to the pintle 13 but on the opposite side of the table. Another clamping frame 18 formed of a single piece of wire 85 is mounted on the said pintle 13 and adapted 90 to swing in substantially the same plane as the said clamp 12. This latter clamp is also provided with a hook 19 for engagement with the rod 16.

For carrying the paper which is usually in 95 roll form 1 have provided a receptacle 20 having a suitable hinged cover 21. A slot is formed in this receptacle as shown at 22 by cutting away a portion of one of the edges of the cover 21 and through which the paper 100 23 is adapted to pass. In connection with this device there is also arranged an indicator 24 and an alarm 25 for indicating and notifying the operator of the number of prints made. In this connection the arm 35 105 strikes the pin 35^a every time the pad is clamped down and the said pin operates the registering mechanism within the box 24^a which in turn operates the hammer 25^a to strike the bell 25 when a certain number of 110 prints are made.

Arranged along the edges of one end of

22
the table and extending approximately to the light opening are the guide members 26 and 27 under which the slide 45 of the aforesaid paper feeding mechanism is adapted to travel. It will be seen that the guide member 27 is provided with a series of notches 28 in which the stop 29 engages. This stop 29 is loosely mounted and adapted to be adjusted longitudinally on the bar 30 to engage 10 the respective notches. Particular attention is called to the fact that the end of the stop member 29 projects through the particular notch in which it may be seated and into the path of the feed slide 45 so as to be engaged 15 thereby in a way to limit the paper feeding movements.

The pad 31 may be of conventional construction and is resiliently connected to the operating member 32 by the springs 33. 20 This member 32 which carries the pad is of suitable rectangular form and may be of any desired material, being provided with the handle 34 for convenient manipulation. Pivoted annular side arms 35 and 36 which 25 form the supporting means for the member 32 extend along the edge of said member and are secured thereto by screws 37. These supporting bars are bent outwardly from the edges of the operating member 32, as 30 indicated at reference numeral 38 to extend beyond the sides of the table and are then bent to extend parallel. The pivot or hinge point is formed at the apex of the angle formed by these bars 35 and 36 and the 35 pintles represented by the screws 39 are mounted in the brackets 40, the latter being suitably secured to the table.

Curved links 41 and 42 connect the ends of the arms 36 with the paper feeding 40 mechanism, each being pivoted at their connections. The paper feeding mechanism comprises the transverse rocker shaft 43 mounted in the brackets 44 which are carried by the slide 45, the latter projecting 45 under the guides 26 and 27 heretofore mentioned. Upon each end of the transverse rocker shaft 43 are secured short arms 46 to which the links 41 and 42 connect. These arms have flanges 46' adapted for engagement with the outer edge of the said links whereby the forward movement of the latter will cause an oscillatory movement of the said rocker shaft 43 and the said fixed arms 46. This oscillatory movement causes the 50 gripping action of the engaging member 48 which is secured to the transverse rocker shaft 43 by means of the screw 47. The face of this engaging member 48 can be serrated as shown and is adapted for clamping the 55 paper against the upper face of the plate 45. Secured to the paper engaging member 48 is the catch 49 for engagement with the bolt 50 having a projecting finger piece carried by the member 32, which carries the pad.

60 The lamps 6 enclosed in the light box are

in proper circuit with the switch whose push button is indicated at 51. This switch which normally is open is operated by engagement with the member 52 carried by the operating member.

70 The operation of the device is as follows:—A supply of print paper being in the receptacle 20 in the form of a roll, one end is threaded through the opening formed therein at 22. The negative is then placed 75 in position on the shoulder 9 above the light transmitting opening and a mask plate 11 placed thereon such as the type of negative may require, the latter being held in position by means of the hinged sheet metal 80 clamping frame 12. The end of the print paper above mentioned is now carried forward across the negative and is clamped firmly in place by means of the wire frame 18, the end of the paper extending sufficiently beyond the end of the negative to permit the engagement of the gripping member 48. During these preparations the 85 pad has necessarily been in a raised position by the elevation of the adjustable member which is now swung downwardly so that the pad is properly seated and in this lowered position it will be seen that the catch 49 engages and locks same firmly. The closing of this operating member through contact with the push button 51 closes the circuit and the lamps are properly illuminated.

90 After a proper time has elapsed the pad and operating member are raised by first gripping the handle 34 drawing the bolt 100 50 and then lifting the operating member which by means of the connections shown causes the paper gripping member 48 to swing downwardly to grip the paper against the plate 45. With the movement of this 105 gripping member the entire paper mechanism moves along the tracks provided until the edge of the plate 45 engages the end of the adjustable stop 29 which projects through one of the notches formed in the 110 track 27. It will be obvious that this will accordingly carry the paper forward a predetermined distance which is regulated by the adjustment of the stop 29. By raising and lowering the operating member as above 115 indicated a regulated amount of paper is fed into position over the negative and subjected to the light from the light box at each operation. When it is desired to print from a new negative of a different size the 120 proper amount of paper can be fed by changing the position of stop mentioned.

125 Various changes in the details of construction may be made without departing from the spirit of the invention.

What I claim as new and useful and desire to secure by Letters Patent, is:—

1. In a photographic printing machine comprising a light box having a light transmitting opening, means for holding a nega- 130

5. In a photographic printing machine comprising a light box having a light transmitting opening, means for holding a negative in position over said opening, a mask for said negative, means for retaining said mask in position, a paper feeding mechanism, and means for regulating said paper feeding mechanism, said regulating means including a feed slide and an adjustable stop member.
6. In a photographic printing machine comprising a light box having a light transmitting opening, means for holding a negative in position over said opening, a mask for said negative, means for retaining said mask in position, a pad and operating member, a paper roll supporting means, means for feeding paper from said roll supporting means into position over said negative, means for regulating said paper feeding means, and means carried by said paper feeding means, for locking said pad and operating member in position.
7. In a photographic printing machine comprising a light box having a light transmitting opening, means for retaining a negative over said opening, a pad and operating member, means for feeding paper into position over said negative, angular pivoted supports for said operating member, links connecting said pivoted supports to said paper feeding mechanism, means for regulating the movement of said paper feeding mechanism, and means carried by said paper feeding mechanism for locking the pad.
8. A photographic printing machine comprising a light box having a light transmitting opening, means for retaining a negative over said opening, a swinging pad, paper feeding mechanism operated by the movement of the pad, paper gripping mechanism carried by said paper feeding mechanism comprising an oscillating grip, and a latch for engaging the said paper gripping mechanism.
9. A photographic printing machine comprising a light box having a light transmitting opening, means for retaining a negative over said opening, a pad and operating member therefor, tracks arranged on said table, paper feeding mechanism traveling on said tracks, gripping means carried by said paper feeding mechanism, and locking means connected to said paper gripping mechanism for locking said pad and operating member in position.
10. In a photographic printing machine comprising a table having a light box arranged thereunder, said light box being provided with a light transmitting opening, means for retaining a negative in position over said light transmitting opening, a pad and operating member therefor, tracks arranged on said table, paper feeding mechanism traveling on said tracks, gripping means carried by said paper feeding mechanism, and locking means connected to said paper gripping mechanism for locking said pad and operating member in position.
11. In a photographic printing machine comprising a table having a light box arranged thereunder, said light box being provided with a light transmitting opening, means for retaining a negative in position over said light transmitting opening, a pad and operating member therefor, tracks arranged on said table, paper feeding mechanism traveling on said tracks, an oscillating paper gripping means carried by said paper feeding mechanism, arms carried by said paper gripping mechanism and having outwardly turned flanges, means connecting said operating member and said arms and engaging said flanges, and locking means connected with said paper gripping mechanism for locking said pad and operating member in position.
12. In a photographic printing machine comprising a table having a light box arranged thereunder, said light box being provided with a light transmitting opening, means for retaining a negative in position over said light transmitting opening, a pad and operating member, tracks arranged upon said table, paper feeding mechanism traveling on said tracks, an oscillating paper gripping means carried by said paper feeding mechanism, arms carried by said paper gripping mechanism and having outwardly turned flanges, means connecting said operating member and said arms and engaging said flanges, and locking means connected with said paper gripping mechanism for locking said pad and operating member in position.
13. In a photographic printing machine comprising a table having a light box arranged thereunder, said light box being provided with a light transmitting opening, means for retaining a negative in position over said light transmitting opening, a pad and operating member, tracks arranged upon said table, paper feeding mechanism traveling on said tracks, an oscillating paper gripping means carried by said paper feeding mechanism, arms carried by said paper gripping mechanism and having outwardly turned flanges, means connecting said operating member and said arms and engaging said flanges, and locking means connected with said paper gripping mechanism for locking said pad and operating member in position.

turned flanges, means connecting said pad and operating member and said arms and engaging said flanges, locking means connected with said paper gripping mechanism for locking said pad and operating member in position, and an adjustable stop for regulating the movement of the paper feeding mechanism.

Signed at Bridgeport, in the county of Fairfield and State of Connecticut, this 20th day of May, A. D. 1920.
